UNITED STATES PATENT OFFICE.

ARTHUR G. MCKEE, OF CLEVELAND, OHIO, ASSIGNOR TO ARTHUR G. MCKEE & COMPANY, OF CLEVELAND, OHIO, A CORPORATION OF DELAWARE.

DISTRIBUTOR DRIVE FOR BLAST-FURNACE STACKS.

Application filed October 9, 1924. Serial No. 742,523.

To all whom it may concern:

Be it known that I, ARTHUR G. MCKEE, a citizen of the United States, and a resident of Cleveland, county of Cuyahoga, and State of Ohio, have invented a new and useful Improvement in Distributor Drives for Blast-Furnace Stacks, of which the following is a specification, the principle of the invention being herein explained and the best mode in 10 which I have contemplated applying that principle so as to distinguish it from other inventions.

The approved modern practice in charging blast furnaces involves the use of two superposed hoppers at the top of the furnace stack, such hoppers being controlled by corresponding axially aligned bells. In the most modern equipment, moreover, the upper hopper with its corresponding bell closure is rotatably supported on the lower and larger hopper in order to facilitate the uniform distribution of the various materials which are initially received in such upper hopper, all as fully set forth in my prior U. 20 S. Patents No. 864,795, dated September 3, 1907, and No. 890,569, dated June 9, 1908.

The present improvements have to do with the mounting of such upper hopper or distributor and to the means provided for thus 30 rotating same. The principal object of the invention is to provide a motor drive that may be mounted on the immediate support for such rotatable hopper or distributor itself, thus doing away with the necessity 35 for any form of extraneous drive. In this way, all mechanism is taken off the platform of the furnace stack, as is highly desirable, and the operation of the furnace as a whole is simplified and rendered more convenient.

40 In other words, I make the entire drive, including the motor, in effect integral with the spider ring which supports the distributor so that the drive may be assembled in the shop, shipped integrally with such 45 spider ring without removing any of its parts, and during operation such drive is held rigidly with all of its parts in proper relation to each other. In case of dismantling the furnace top for replacement of 50 a bell, or otherwise, the spider casting and such drive may be removed and set aside as one piece and when the top is reassembled, they merely require to be set back in place

without the interrelation of the several parts being in any way disturbed.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a side elevation of a furnace stack equipped with my improved distributor drive; Fig. 2 is a plan view of the same; Fig. 3 is a side elevation thereof, as viewed from the right in Figs. 1 and 2; and Figs. 4 and 5 are vertical sections taken on the planes indicated by the lines 4—4 and 5—5; Figs. 1 and 2.

In the drawings, only the upper wall 1 of the cover or cap for the lowermost of the two hoppers provided at the top of the furnace stack is shown, such wall being in the form of a frusto-conical cap suitably supported on the upper end of the furnace shaft (not shown). Mounted in turn on such cap 1 is a cylindrical shell 2 that constitutes the body of the second hopper or distributor. As previously indicated, such distributor requires to be rotatably supported; in fact it derives its name from this circumstance. As best shown in Figs. 4 and 5, the main elements of such rotatable mounting are a base in the form of a spider ring casting 3 that is suitably supported on the flanged neck 4 that surmounts cap 1; an annular ball race 5 that is in turn supported on the upper face of said spider ring casting; and a complementary ball race 6 that is bolted to a laterally projecting flange 7 on the distributor 2. The balls 8 interposed between the races 5 and 6, it will thus be seen, serve rotatably to support said distributor on the upper end of cap 1. The lower ball race 5 is provided with downwardly opening apertures 9 at spaced intervals to permit the escape of dust or like matter from such race.

The spider ring 3, it will be noted, is formed with a flange 10, the inner end of which is beveled inwardly and upwardly so as to overlie a flange 11 of complementary

form that projects outwardly from the body 2 of the distributor, only enough clearance being left between the two flanges to permit of the free rotation of the distributor while assuring an effective gas seal between the latter and the top of the cap 1.

The upper ball race 6 is formed about its entire circumference (see Figs. 1, 2 and 3) with gear teeth 15 that constitute thereof an annular rack and the drive mechanism of interest in the present connection co-operates with such rack to rotate the distributor 2 in desired manner. Such drive mechanism is wholly supported on a depending bracket 16 that is attached to the oppositely directed face of the spider ring casting at one point, or rather at several adjacent points, in its circumference. The bracket is of sufficient extent to accommodate an electric motor 17, and in alignment therewith, a worm gear drive 18, the motor spindle being connected with such drive through the medium of a flexible coupling 19. A vertical spindle 20, on which is mounted a worm gear 21, comprises one member of such drive and lies in offset relation to the common axis of the motor and of the worm 22 that constitutes the other member of the drive, said spindle being journaled in suitable bearings on said bracket at its lower end and at an intermediate point and being provided at its upper end with a spur pinion 23 that meshes with the teeth of the annular rack 15. Associated with the motor 17 is a suitable brake 25 and a limit switch 26, of standard design, whereby the motor may be caused to rotate the annular rack 15 and thus the distributor shell a predetermined amount and then stop.

From the foregoing description, the operation of my improved drive as a whole should be readily understood. The arrangement of the motor with its axis approximately tangential to the spider ring casting 10 and annular ring 15 with the offsetting inwardly of the spindle 20, that carries the drive pinion 23, makes for an exceedingly compact and at the same time efficient mechanism. While the ring affords an adequate support for bracket 16 and the mechanism thus carried thereby, it will be understood that the latter may be additionally or wholly supported with the parts in corresponding position on cap 1.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In charging mechanism for blast furnaces, the combination of a rotary distributor; a base ring providing an annular sup-

port for the bearing for said distributor; and driving means for said distributor carried wholly by said ring.

2. In charging mechanism for blast furnaces, the combination of a rotary distributor; a base ring providing an annular support for the bearing for said distributor; and driving means for said distributor, said means including a worm and worm gear carried wholly by said ring. 70

3. In blast-furnace charging mechanism, the combination of a rotary distributor; a base ring providing an annular support for the bearing for said distributor; and a motor and driving gear connecting the same with said distributor, said motor and gear being carried by said ring, whereby said distributor and the driving mechanism therefor may be placed on and removed from the furnace top in assembled condition. 80

4. In blast-furnace charging mechanism, the combination of a rotary distributor; a base ring providing an annular support for the bearing for said distributor; a bracket depending from and wholly supported by said ring; and a motor and driving gear connecting the same with said distributor, said motor and gear being carried by said bracket, whereby said distributor and the driving mechanism therefor may be placed on and removed from the furnace top in assembled condition. 90

5. In blast-furnace charging mechanism, the combination of a rotary distributor; a base ring providing an annular support for the bearing for said distributor; an annular gear attached to and extending circumferentially around said distributor; a bracket depending from and wholly supported by said ring; a vertical spindle mounted on said bracket and provided with a pinion in mesh with said gear; and a motor and reduction gearing connecting the same with said spindle, said motor and gearing being likewise carried by said bracket, whereby said distributor and the driving mechanism therefor may be placed on and removed from the furnace top in assembled condition. 100

6. In blast-furnace charging mechanism, 105

the combination of a rotary distributor; a base ring providing an annular support for the bearing for said distributor; an annular gear extending circumferentially around said distributor; a bracket depending from and wholly supported by said ring; a vertical spindle journaled in suitable bearings on said bracket at its lower end and at an intermediate point and provided at its upper end with a pinion in mesh with said annular gear; a worm gear fixed on said spindle between its aforesaid bearings in said bracket; a worm meshing with said worm gear; and a motor coupled with said worm, said motor and worm likewise being car- 110

ried by said bracket, whereby said distributor and the driving mechanism therefor along with said ring may be placed on and removed from the furnace top in assembled 5 condition.

7. In blast-furnace charging mechanism, the combination of a rotary distributor; a base ring providing an annular support for the bearing for said distributor; an annular 10 gear extending circumferentially around said distributor; a bracket depending from and wholly supported by said ring; a vertical spindle journaled in suitable bearings on said bracket at its lower end and at an intermediate point and provided at its upper 15 end with a pinion in mesh with said

annular gear; a worm gear fixed on said spindle between its aforesaid bearings in said bracket; a worm meshing with said worm gear; and a motor coupled with said worm, said motor and worm likewise being carried by said bracket, whereby said distributor and the driving mechanism therefor along with said ring may be placed on and removed from the furnace top in assembled condition, the axis of said motor and of the worm coupled therewith being approximately tangential to said ring and said spindle being offset inwardly with respect thereto. 20 25 30

Signed by me this 4 day of October, 1924.

ARTHUR G. McKEE.
